US0D1060182S

(12) **United States Design Patent** (10) **Patent No.:** **US D1,060,182 S**
(45) **Date of Patent:** **** Feb. 4, 2025**

(54) **VEHICLE WHEEL**

(71) Applicant: **Toyota Motor North America, Inc.**,
Plano, TX (US)

(72) Inventors: **Alberto Echazabal**, Prosper, TX (US);
Jakin C. Wilson, Prosper, TX (US)

(73) Assignee: **Toyota Motor North America, Inc.**,
Plano, TX (US)

(**) Term: **15 Years**

(21) Appl. No.: **29/892,534**

(22) Filed: **May 18, 2023**

(51) **LOC (15) Cl.** **12-16**

(52) **U.S. Cl.**
USPC **D12/209**

(57) **CLAIM**

The ornamental design for a vehicle wheel as shown and described.

DESCRIPTION

FIG. 1 is a front perspective view of a vehicle wheel illustrating our new design;

FIG. 2 is a rear perspective view thereof;

FIG. 3 is a front elevation view thereof;

FIG. 4 is a rear elevation view thereof; and,

FIG. 5 is a side elevation view thereof.

The broken lines in the drawings illustrate portions of the vehicle wheel that form no part of the claimed design. The dot-dashed lines are included for the purpose of illustrating boundary lines and form no part of the claimed design.

1 Claim, 5 Drawing Sheets
